UNITED STATES PATENT OFFICE.

ALBERT E. DURLAND, OF STAPLEHURST, NEBRASKA.

BUCKLE.

SPECIFICATION forming part of Letters Patent No. 699,502, dated May 6, 1902.

Application filed October 4, 1901. Serial No. 77,592. (No model.)

To all whom it may concern:

Be it known that I, ALBERT E. DURLAND, a citizen of the United States, and a resident of Staplehurst, in the county of Seward and State 5 of Nebraska, have made a certain new and useful Invention in Buckles; and I declare the following to be a full, clear, and exact description of the same, such as will enable others skilled in the art to which it appertains to 10 make and use the invention, reference being had to the accompanying drawings, and to letters of reference marked thereon, which form a part of this specification.

Figure 1 is a perspective view of my buckle 15 as applied. Fig. 2 is a side elevation of the same on a larger scale and partly broken away. Fig. 3 is a perspective view of the wedge-section. Fig. 4 is a perspective view of the socket-section.

20 This invention has relation to harness-buckles, and has for its object to provide a fastening or buckle of novel and efficient character for the ends of straps which will have no sharp or pointed projecting portions 25 to catch upon fly-nets or to catch the tail of the horse, which will be adjustable, and will require no perforations in the straps for fastening rivets.

With these objects in view the invention 30 consists in the novel construction and combination of parts, all as hereinafter described, and pointed out in the appended claim.

In the accompanying drawings, illustrating the invention, the device is shown as applied 35 to fasten the ends of a strap when looped for a snap-hook to the body of the strap, as in the case of a brace, although the buckle is equally well adapted for use for almost all buckles used upon harness.

40 In the drawings the letter A designates the end of a brace-strap, and B is my buckle,

consisting of a socket-section B' and a wedge-section B², interfitting to form the fastening. The socket-section B' is of box form open at both ends for the insertion of the strap end, 45 has upper and lower walls of an inclination with respect to each other, and is preferably formed of sheet metal. The wedge-section B² is also preferably formed of sheet metal, having lateral guard-walls b' and reversely 50 bent or doubled to form the spring wedge-tongue b², separated by an interval from the base of the wedge and inclosed between such walls and wedging against the outer inclined wall of the socket-section when the parts are 55 drawn together, the rear portion of said tongue projecting from the socket-section for ready depression to release the fastening when desired.

In securing the two sections of my buckle 60 to the strap I punch small holes in the metal of the same from within outwardly, the metal standing up around such holes to form the outer sharp-pointed or jagged projections c, which dig into the surface of the leather strap 65 sufficiently to secure the parts in their adjustments.

Having thus described my invention, what I claim as new, and desire to secure by Letters Patent, is—

A buckle or strap fastening comprising the socket-section, and the wedge-section fitting therein, and having the spring wedge-tongue separated by an interval from the base of the wedge, and the lateral guard-walls for said 75 tongue, substantially as specified.

In testimony whereof I affix my signature in presence of two witnesses.

ALBERT E. DURLAND.
